UNITED STATES PATENT OFFICE.

EVERETT B. GLENDENNING, OF EAST DEDHAM, MASSACHUSETTS, ASSIGNOR OF ONE-HALF TO MILTON A. FESLER, OF STAMFORD, CONNECTICUT.

AMUSEMENT APPARATUS.

1,369,525.

Specification of Letters Patent. Patented Feb. 22, 1921.

Application filed March 28, 1917. Serial No. 158,139.

To all whom it may concern:

Be it known that I, EVERETT B. GLENDENNING, a citizen of the United States, and resident of East Dedham, county of Norfolk, and the Commonwealth of Massachusetts, have invented an Improvement in Amusement Apparatus, of which the following description, in connection with the accompanying drawings, is a specification, like characters on the drawings representing like parts.

This invention relates to amusement apparatus, and particularly to dancing figures adapted to be used in connection with and actuated by a motor as, for instance, a talking machine.

In the drawings of one embodiment of my invention illustrated and described herein:

Figure 1 is a side elevation of the apparatus in position for use on a talking machine, the cabinet partly broken away;

Fig. 2 is an end elevation from the left, Fig. 1; and

Figs. 3 and 4 are details of modified forms of locking means for supports of different designs.

My invention is shown as an apparatus that may be readily secured to the cabinet of any conventional talking machine cabinet; and referring first to Figs. 1 and 2, is illustrated as comprising first a longitudinal base or support 1, of suitable material as wood, which rests upon the top of the cabinet near its edge, and having a figure carrying upper or post 2, secured thereon.

At one end of the base, opposite the post 2, it may be fashioned to provide a platform 3 of convenient size, or the platform may be constructed separately and secured thereto.

For securing the base 1 in position on the cabinet, the post 2 may be provided with a suitable clamp. Herein, Fig. 2, it carries an angular locking member 4 secured to the edge of the post 2, as by screws, and carrying

on its outwardly extended end 5 a thumb nut 6 to secure thereto one arm of a U-shaped member 7, the opposite arm being locked against the lower face of the overhanging edge 8 of the cabinet top by a lock screw 9. Suitable cushion members 10, may be provided, if desired, to prevent marring the cabinet.

For yieldingly supporting the dancer, the post 2 may be provided with a spring or

other suitable resilient member 11, one end 12 of which may be adjustably secured to the post by a screw 13 while the other end 14 is secured in any convenient manner to the dancer 15, preferably between its extremities, thereby giving it greater freedom of action. Herein, for convenience, the spring end is extended through the body of the dancer, which may be suitably secured thereon. The spring may also be adjusted at the top of the post by any suitable means as a screw 16.

The body of the dancer may be of any light material as wood, having its legs 17, 18, pivoted thereto. I have discovered that if one leg, 17, is made slightly longer than the other, a much greater variety of steps and contortions will be produced, as the figure will, by that means, be effectively prevented from alighting on both feet simultaneously.

For transmitting motion to the dancer, I provide a block 19 on the support 2, see Fig. 1, dotted lines, which carries in a vertical slot 20 therein a shaft 21, on the opposite end of which is mounted a wheel 22 having a frictional yielding surface 23 of rubber. This surface engages the upper face of a record tablet 24 on the turntable 25, and is rotated thereby.

The shaft 21 is adjustable vertically in the slot 20 to permit proper engagement of the wheel 22 with tablets of varying thickness, and may be locked in proper position by a thumb nut on the shaft engaging the block, not shown.

The wheel 22 carries a wrist pin 26 adjustably positioned in a slot 27 therein by a nut not shown, and to the pin one end of a rod 28 is pivotally secured, while its opposite end is slotted at 29 and receives therein a guide pin 30 on the end of a bracket 31 on the post 2.

Obviously, as the wheel 22 rotates, the upper end of the rod 28 will hit the spring 11 at each reciprocation thereof and impart a series of upward thrusts to the spring and raise the dancer from the platform. The figure being suspended between its head and feet, it is free to rise and fall with the vibrations of the spring 11 between the successive contacts of the rod 28 therewith, which results in keeping the figure constantly in action. The wooden feet 32 strike the plat-

form sufficiently loudly to be clearly noticeable above the noise of the talking machine.

One leg of the dancer being longer than 5 the other, the figure never strikes upon both feet squarely and one leg is always bent or swinging loosely each time the foot on the other leg contacts with the platform.

This gives a much greater variety to the 10 steps of the dancer, and causes it to go through certain motions and gymnastics that are performed by no other similar figure so far as I know. By adjusting the tension of the spring 11 through the screw 16 15 and by adjusting the position of the pin 26 on the wheel 22, thereby determining the extent of the thrust imparted to the member 11, and thus the distance the figure is raised from the platform, the frequency of the 20 steps of the figure may be caused to coincide with the time of the music.

If desired, an adjusting screw 33 may be provided extending through the base 2 and 25 engaging the surface of the cabinet for raising or lowering the base 2 to correspond to the thickness of the tablet 24, and this will avoid the necessity of adjusting the shaft 21.

In Fig. 3 I have illustrated a modified 30 form of locking member for use upon cabinets having a raised edge or flange 34.

In this case an angle member 4 is used having a downwardly extended arm 35 to contact with the flange 34 and an additional 35 spring 36 is secured to the shoulder 37 on the post 2, the spring spanning the edge 34 and resting on the arm 35. Cushion material 10 may also be used in this case.

In Fig. 4 I illustrate a convenient form 40 of locking means for use on an ornamented or beveled edge 34. In this case the angle member 4 is secured to the post 2 upside down as compared with Fig. 2, but carries the member 7, Fig. 2, at its outer end as before and an additional angle member 38, 45 slotted for convenient adjustment, is locked to the post 2 by a screw 39 with its arm, not shown, resting against the inner face of the edge 34. In all of these cases the adjustment is such that the wheel 22 contacts with 50 the record tablet or disk near its edge.

It is obvious that the foregoing embodiment of my invention may be modified in many detailed respects, all within the spirit of the invention and the scope of the appended claims.

Claims:

1. A dancing figure apparatus comprising a base, a figure having legs of unequal length, a yielding support therefor between 60 its extremities, a rotatable member adjacent the base, and means for transmitting motion to the figure through the yielding support from the rotatable member.

2. A dancing figure apparatus comprising 65 a base, a figure having legs of unequal

length, a yielding support therefor between its extremities, a rotatable member adjacent the base, and means actuated by the rotatable member to impart a series of upward thrusts to the yielding support.

3. A dancing apparatus comprising a base, 70 means for locking it to a support, a figure support on the base, a figure resiliently carried between its extremities by its figure support, means on the base to engage a movable member and impart motion to the figure, and means to lock the base to the extended edge of a cabinet.

4. A dancing figure apparatus comprising 75 a base, means for locking it to a support, a figure support on the base, a figure having legs of unequal length both resting on the platform and resiliently carried between its extremities by its figure support, and means on the base to engage a movable member and 80 impart movement to the resilient carrying member between the figure and its support.

5. A dancing figure apparatus comprising 85 a base, means for locking it to a support, a figure support and a platform on the base, a figure having legs of unequal length resiliently carried between its extremities by its support, means on the base to engage a movable member and impart motion to the figure, and means on the base to adjust it to 90 enable the motion-receiving means to receive and impart motion to the figure.

6. A dancing figure apparatus comprising 95 a base, means for locking it to a support, a figure support on the base, a figure having 100 legs of unequal length resiliently carried between its extremities by its figure support, means to regulate the tension of the spring and frequency of the dancing steps of the figure, and means on the base to engage a 105 movable member and impart movement to the figure.

7. A dancing figure apparatus comprising, in combination a base to be locked to a talking machine cabinet, locking means 110 therefor, a figure support on the base, a figure having legs of unequal length, resilient figure-carrying means engaging the figure between its extremities, a wheel on the base to engage a record tablet, and a rod adjustably pivoted to the wheel and adapted to contact with the resilient figure-supporting means to impart motion to the figure in time with the music.

8. A dancing apparatus comprising a base, 115 means thereon for locking the base to a laterally and a perpendicularly extended edge of a cabinet, said means comprising a locking member adapted to embrace said extended edge with means for clamping the same thereto, a figure support on the base, a figure resiliently carried between its extremities by its figure support, and means on the base to engage a movable member to 120 impart motion to the figure.

9. A dancing figure apparatus comprising the base 1, having the support 2, and platform 3, the resilient figure supporting member 11 on the support 2, the figure 15 on the 5 resilient member, the movable member 22 on the support adapted to engage the rotatable member beneath the platform 3, and

the thrust rod 28 on the member 22 for engaging the resilient figure supporting member to impart motion thereto. 10

In testimony whereof, I have signed my name to this specification.

EVERETT B. GLENDENNING.
